FUNNEL FOR FLOWER ARRANGEMENTS

David B. Anderson, Jr., 5526 Douglas Drive,
Crystal, Minn. 55429

Filed July 18, 1973, Ser. No. 380,392

Term of patent 14 years

Int. Cl. D11—02

U.S. Cl. D35—3 A

FIG. 1

FIG. 3

FIG. 2

FIG. 4

FIG. 5

FIG. 1 is a view in perspective as seen from the front, one side and the top of a funnel for flower arrangements showing my new design;

FIG. 2 is a view in rear elevation thereof;

FIG. 3 is a view in top plan thereof;

FIG. 4 is a side elevational view thereof as seen from the side opposite that seen in FIG. 1; and

FIG. 5 is a view in bottom plan thereof.

I claim:

The ornamental design for a funnel for flower arrangements, substantially as shown.
